SERVO-CONTROL VALVE FOR
HYDROSTATIC PUMPS

Jean Paul Polouektoff, Paris, France

Application November 19, 1948, Serial No. 60,905
In France November 20, 1947

9 Claims. (Cl. 103—5)

1

The present invention relates to a hydraulic servo-control valve that provides automatic and uninterrupted operation of immersed pumps in which the filling is produced by the hydrostatic pressure with or without the assistance of an injector, whereas the delivery is produced by the pressure of a fluid, for example compressed air, on the liquid to be delivered.

A plant of this type essentially comprises a pump formed of two containers associated with an air distributor which successively and alternately places one of the ends of each of the containers in communication with the compressed air supply and with the air exhaust pipe, while the opposite ends of said containers are alternately and successively placed in communication with the delivery pipe for the liquid and with the inlet ports for said liquid, so that each of the containers is in the delivery phase while the other is in the filling phase and vice-versa.

The change of phases in existing pumps of this type is produced by the movement of a group of floats which actuates the air distributor.

The floats have the following drawbacks:

1. The emptying of the compartment in which the pump is immersed is limited by the minimum height required for the operation of the floats.

2. In order to be sufficiently reliable in operation, the floats must be fairly buoyant and be fairly heavy, thereby involving a correspondingly large size and limiting the minimum dimensions of the cylinders.

3. There is danger of the floats being burst by the pressure of the air when the particular conditions of use of the pump require a high pressure.

Heretofore this has prevented the manufacture of pumps of this type of small size and low output for which there is a demand in certain branches of industry, for example in boring operations.

The present invention overcomes these various drawbacks and provides a servo-control valve which automatically controls the distributor of pumps of the type in question, without involving the use of any float.

The chief advantages and features of this servo-control valve will become apparent from the ensuing description made with reference to the accompanying drawing, the single figure of which shows a longitudinal section of an embodiment of a hydrostatic pump provided with a servo-control valve according to the invention.

The hydrostatic pump to which the servo-control valve according to the invention has been assumed to be applied, essentially comprises a container 3 and a container 4 which may be of

2

any shape (cylindrical or otherwise) and may be superposed, separate or contiguous (it is the latter case that has been illustrated). These two containers, which are of substantially the same volume and are adapted to operate successively, form the two cylinders of the pump.

These two cylinders 3 and 4 are bounded at their upper part by a delivery chamber 5 and at their lower part by a suction chamber 6 which is connected to the cylinders through inlet valves 8a, 9a, whereas the chamber 5 is connected to said cylinders through delivery valves 8r, 9r. Said valves 8r, 9r, may be constructed in any suitable known manner, but they are loaded in such a manner as to produce a constant pressure-drop of a predetermined minimum value (for example 0.150 kg. per sq. cm.).

Said two cylinders 3 and 4 are alternately and successively placed in communication, by means of a distributor, either with a source of compressed air 12 (or of steam), or with the exhaust pipe 13. According to a modification, said exhaust pipe could be connected to the suction pipe of the compressor.

The distributor comprises a body 19 in which a balanced piston-valve 20 is adapted to move. Said body 19 is adapted to be placed in communication:

a. With the source of compressed air 12 by means of the duct 21 which opens into said body through the port 22, a pressure regulating device, which will be described hereinafter being inserted between said duct 21 and the source 12.

b. Through the ports 23 and 23a and the duct 24, either, as shown, with the surrounding medium (water or atmospheric air) which surrounds the upper cover of the delivery chamber 5, or, according to the modification hereinbefore considered, with the suction pipe of the compressor.

c. With the upper part of the cylinder 3 through a port 25 and a duct 26.

d. With the upper part of the cylinder 4 through a port 27 and a pipe 28.

The distribution valve 20 may assume two positions:

a. The high position (position shown), in which it places in communication, on the one hand, the cylinder 4 with the compressed air supply pipe 12, and, on the other hand, the cylinder 3 with the exhaust pipe 13.

b. The low position, in which it places in communication, on the one hand the cylinder 4 with the exhaust pipe 13, and on the other hand the cylinder 3 with the compressed air supply 12.

According to the present invention, said piston-valve 20 is abruptly shifted from one position to

the other, and conversely, by the action of a servo-control valve comprising a balanced piston-valve 124 adapted to move in a cylinder 125 by the reciprocating action of a push-rod 126 secured to a piston 127 adapted to move in a cylinder 128 and of a push-rod 129 secured to a piston 130 adapted to move in a cylinder 131.

Furthermore, the piston-valve 124 is subjected to the action of a lever 132 on which a spring 133 acts by means of any suitable device, for example a ball. Said spring 133 may be of any suitable type (helical, spiral or other type) and its adjustable tension is determined as will be described hereinafter.

The outer end of the cylinder 128 is connected through a pipe 134 to the cylinder 3 and the outer end of the cylinder 131 is connected through a pipe 135 to the cylinder 4.

The inner ends of the two cylinders 128 and 131 are connected through the pipes 136 and 137 to the delivery chamber 5. This connection may be effected in two ways:

a. Either directly, in which case the pipes 136 and 137 are filled with the liquid delivered which passes beforehand through a filter 138.

b. Or indirectly, in which case the pipes 136 and 137 are filled with oil or any incompressible liquid, the pressure in the chamber 5 being transmitted to said liquid by a suitable fluid-tight diaphragm which replaces the filter.

In both cases, the flow of the liquid through the pipes 136 and 137 can be braked at will by means of the two adjusting screws 139 and 140.

The cylinder 125 is provided with a plurality of ports, viz., a central port 151 connected through a pipe 152 to the source of compressed air 12 on the upstream side of the pressure regulator which will be described hereinafter; a port 153 connected through a pipe 154 to the upper part of the cylinder 19 of the distributor; a port 155 connected through a pipe 156 to the lower part of this same cylinder; and two ports 157 and 158, one at the upper part, the other at the lower part of the cylinder 125 and both connected to the exhaust pipe 24.

The valve 124 can assume two positions:

a. A high position, in which it places in communication, on the one hand the top of the cylinder 19 of the distributor with the source of compressed air 12 through the ports 151 and 153 and the pipe 154, and on the other hand, the bottom of the cylinder 19 with the exhaust pipe 24 through the pipe 156 and the ports 155 and 158.

b. A low position, in which it places in communication, on the one hand the bottom of the cylinder 19 with the source of compressed air 12 through the ports 151 and 155 and the pipe 156, and, on the other hand, the top of the cylinder 19 with the exhaust pipe 24 through the pipe 154 and the ports 153 and 157.

In the position shown in the figure, the distributor has just been shifted into the high position and the pressure fluid is beginning to be admitted through the port 27 and the pipe 28 into the pump cylinder 4 which is then in the delivery phase. The manometric pressure in said cylinder is then equal to:

$$P = Gx + \Delta p$$

wherein Gx is the hydrostatic pressure in the delivery chamber 5 and Δp the internal pressure-drop in the pump, in particular in the internal pipes and the delivery valves 8r and 9r. Said pressure P acts through the pipe 135 on the lower

face of the piston 130 of the servo-control valve.

On the other hand, in the cylinder 3, which starts in the filling phase, there is only the hydrostatic filling pressure H which acts through the pipe 134 on the upper face of the piston 127. Thus, in the position shown in the figure, the piston 130 is subjected on its lower face to the pressure P through the pipe 135, and on its upper face to the pressure Gx through the pipe 137; during the same period, the piston 127 is subjected on its lower face to the pressure Gx through the pipe 136 and on its upper face to the pressure H through the pipe 134.

The piston 130 is therefore urged upwards by the differential pressure Δp . The piston 127 is likewise urged upwards by the difference between the two pressures $Gx - H$.

Since the piston 127 is independent of the piston-valve 124 and of the piston 130, its movement by the action of $(Gx - H)$ can take place separately and does not exert any effect on the movement of the piston 130 and of the piston-valve 124, which remain solely affected by the differential pressure Δp and the spring 133. The differential pressure Δp thus causes the piston-valve 124 to move upwards. At the beginning of this movement, said piston-valve closes the port 155, but the compressed air confined in the pipe 156 continues to retain the balanced piston-valve 20 of the distributor in the high position. During the first half of its stroke, the piston-valve 124 tensions the spring 133 which then assists in the completion of the second half of said stroke at the end of which said piston-valve 124 places the port 153 in communication with the compressed air inlet port 151 and the port 155 in communication with the exhaust pipe 158. The compressed air thus acts on the upper face of the piston-valve 20 of the distributor and abruptly moves it into the low position, thereby reversing the phases of the operation of the two pump cylinders. The cycle of operations thus continues without interruption.

The pressure in the cylinders 3 and 4 can be transmitted to the pistons 127 and 130, either directly by means of the liquid delivered, or by means of a liquid that fills the pipes 134 and 135 which are fluid-tightly closed and are provided with diaphragms at the lower part thereof.

The action of the spring 133 constrains the piston-valve 124 to travel up to one of its extreme positions, thereby ensuring the starting of the pump after it has been stopped. The movement of the piston-valve 124 cannot be abrupt owing to the hydraulic braking exerted by the liquid that fills the pipes 136 and 137 and the section of which is reduced by the adjusting screws 139 and 140. The more or less complete closing of the passage enables the movement of the pistons 127 and 130 to be more or less slowed down and, consequently, other things being equal, the movement of the piston-valve 124 to be slowed down and the changes of phase of the pump to be spaced a longer time apart and therefore the speed of the pump to be reduced.

It is obviously necessary for the differential pressure Δp (which corresponds to the pressure-drop) to be sufficient to cause the piston-valve 124 to move, and for said pressure to be constant in order to ensure a smooth operation of the pump.

This result is obtained, on the one hand by loading the delivery valves 8r and 9r, and on the other hand by means of the pressure regulator hereinbefore mentioned. It has, in fact, been

shown that the differential pressure $\Delta p = P - Gx$. Now, Gx varies with the height of delivery. The pressure P must therefore vary under the same conditions. This is what enables the pressure regulator to be obtained.

This regulator, which is inserted between the air supply pipe 12 and the duct 21 of the air distributor, essentially comprises a balanced valve 47 adapted to move in a cylinder 48 which is provided with an opening 49 through which compressed air enters said cylinder, and with two openings 50 through which said air reaches the duct 21 and thence flows into the distributor. Said valve 47 is controlled by a hydrostat 51 formed by a deformable member 52 (piston, diaphragm, bellows or any other like member) which is subjected, on the one hand to the hydrostatic delivery pressure Gx and to the action of the counterweight 53, and on the other hand to the pressure P of the air in the cylinder 48. At the initial adjustment, the counterweight is adjusted in such a manner that for a predetermined hydrostatic pressure Gx , the valve 47 is in a position in which it uncovers the opening 49 to such an extent that the pressure of the compressed air is the pressure required to effect the emptying of a cylinder in the desired time T_2 , equal to the filling time T_1 . If the pressure of the air falls below the useful delivery pressure, the valve 47 moves downwards and opens the port 49 wider, thereby increasing the pressure to the desired value. Conversely, if the pressure of the air becomes greater than the useful pressure, the valve 47 covers the port 49 more. An automatic regulation of the pressure P of the air is thus obtained. The time T_2 required for the delivery will therefore be kept practically constant, irrespective of the value of Gx and for each of the cylinders 3 and 4, and can be adjusted by acting on the screws 139 and 140.

In order to prevent water from entering the ducts of the distributor, a floating valve 150 is provided at the end of each of the pipes 26 and 28 that connect said distributor to the cylinders 3 and 4, so that when the water reaches the upper part of the corresponding cylinder, said valve 150 is lifted and hermetically closes the end of the associated pipe.

The filling of the pump cylinder 3 is assisted by an injector 142, by means of the pressure set up in the adjacent cylinder 4 which is in the delivery phase. An identical injector 143 performs the same function for the cylinder 4. These injectors 142 and 143 operate with water or with compressed air. They enable the pump to effect the complete draining of the compartment in which it is immersed and even of imparting to said compartment a certain suction power.

In the compressed air supply pipe 12 is inserted a butterfly-valve 160 which is retained by a float 161 in the open position so long as the level of the water to be pumped is above the upper part of the pump. When this level falls below this limit, the butterfly-valve 160 assumes the closed position in which the compressed air can only pass through the perforations 162 provided in said butterfly-valve.

It is moreover obvious that the invention has only been described and illustrated herein in an explanatory and in no way limitative manner and that any useful modifications may be made therein without exceeding its scope.

I claim:

1. A hydrostatic pump combination comprising a housing having two alternately acting pump

cylinders, a delivery chamber and a suction chamber, connections between said pump cylinders respectively and said delivery and suction chambers, delivery and inlet valves controlling said connections, an exhaust pipe, a source of compressed fluid, a distributor alternately and successively placing in communication said pump cylinders with the source of compressed fluid and with the exhaust pipe, a servo-control valve in fluid communication with the distributor abruptly actuating said distributor and comprising a balanced piston-valve, two oppositely located cylinders, a piston working in each of said cylinders, means operatively connecting each of said pistons to said balanced piston-valve, one of said two cylinders being connected, to one of the two said pump cylinders, and the other of said cylinders being connected to the other of said pumping cylinders, and said cylinders being connected to the said delivery chamber of the pump, whereby the pressure $P = Gx + \Delta p$ (wherein P is the pressure of the compressed fluid, Gx the hydrostatic delivery pressure, and Δp the pressure-drop) in the pump cylinder which is in the delivery phase actuates the piston in the cylinder connected to said pump cylinder by engaging one face thereof, the opposite face of the piston being subjected solely to the action of the delivery pressure $Gx < P$, whereas the piston in the opposite cylinder moves independently in the same direction due to the fact that it is subjected to the differential pressure between the delivery pressure Gx and the hydrostatic filling pressure $H < Gx$.

2. A hydrostatic pump combination according to claim 1, wherein the distributor has opposing ends adapted to be placed in communication selectively with the source of compressed fluid and with the exhaust and the balanced piston-valve thereof is successively moved by said pistons from a first position, in which position it places the compressed fluid supply in communication with one end of the said distributor of the pump, and the other end of said distributor in communication with the exhaust, thereby causing the said distributor to move into one of its two possible positions and to be retained in that position, into a second position in which the connections are reversed, whereby at the end of each stroke the servo-control valve controls the distributor to place one cylinder of the pump in the filling phase and the other cylinder in the emptying phase, or conversely.

3. A hydrostatic pump combination according to claim 1 wherein a spring is provided and is positioned to be tensioned by the piston-valve during the first half of its stroke from the first portion to the second position, said spring biasing said piston-valve during the completion of the second half of the stroke.

4. A hydrostatic pump combination according to claim 1 wherein in order to make the differential pressure $\Delta p = P - Gx$ sufficient to actuate the piston-valve thereof, means are provided to increase said pressure by loading the delivery valves of the pump.

5. A hydrostatic pump combination according to claim 1 wherein in order to make said differential pressure remain substantially constant irrespective of the variations of the hydrostatic delivery pressure, means are provided for automatically regulating the pressure of the compressed fluid proportionally to said hydrostatic pressure Gx .

6. A hydrostatic pump combination according

to claim 1 wherein means are provided for automatically regulating the pressure of the compressed fluid, said means comprising a regulator connected to the distributor, a valve controlling the connection between the regulator and the distributor, an adjustable counterweight acting on said valve in couple with the action of the hydrostatic pressure G_x and said valve being subjected to the pressure of the compressed fluid admitted to the distributor, said regulator controlling said valve which opens more or less the inlet of said compressed fluid.

7. A hydrostatic pump combination according to claim 1 wherein means are provided for regulating the duration of each of the two strokes of said piston-valve.

8. A hydrostatic pump combination according to claim 1 wherein a connection is provided between the said cylinders and an adjustable hy-

draulic brake is operatively attached to said connection between the cylinders to control the fluid flow therethrough and brake more or less the movement of each of the two pistons that actuate the piston-valve, in order to control the duration of each of the two strokes of said piston-valve.

9. A hydrostatic pump combination according to claim 1 wherein an injector is provided for 10 each of the two pump cylinders and is supplied with the pressure fluid fed to the pump cylinders when they are in the delivery phase, in order to assist in the filling of either of the pump cylinders, in particular when the level of the 15 water to be pumped is near the bottom of the pump.
